CLAIM

The ornamental design for an armored car, as shown and described.

DESCRIPTION

FIG. 1 is a top plan view of an armored car showing my new design;

FIG. 2 is a side elevation view thereof, the opposite side being a mirror image of the side shown herein;

FIG. 3 is a front elevation view thereof;

FIG. 4 is a rear elevation view thereof;
The tires have been fragmentarily shown in FIG. 2 of the drawing for convenience of illustration.

FIG. 1
